UNITED STATES PATENT OFFICE

2,044,982

SANDING MACHINE

Theron L. Hedgpeth, Oak Park, Ill., assignor to
 Duro Metal Products Company, Chicago, Ill., a
 corporation of Illinois

Application March 6, 1935, Serial No. 9,529

5 Claims. (Cl. 51—170)

The present invention relates to sanding machines, and is particularly concerned with portable abrasive devices adapted to be used for sanding or smoothing operations.

One of the objects of the invention is the provision of an improved portable sanding machine adapted to be driven by means of a flexible shaft and an electric motor or other suitable source of power.

Another object of the invention is the provision of a portable sanding machine which is adapted to be driven by means of a motor and flexible shaft and adapted to be manipulated with greater ease and better effect, due to its lightness and simple structure.

Another object of the invention is the provision of a portable sanding machine of the type having an abrasive band which is adapted to be utilized in sanding operations in corners and other relatively inaccessible places so that practically all of a floor area or other similar area may be subjected to the sanding operation by means of the machine.

Another object of the invention is the provision of an improved sanding machine which is portable and which is provided with an abrasive of the belt type having an improved arrangement for tensioning the belt and also having an improved backing surface for supporting the active or working part of the belt.

Another object of the invention is the provision of an improved portable sanding machine which is simple in construction, capable of economical manufacture and assembly, durable and adapted to be manufactured in large quantities at a very low cost so that it can be placed within the reach of a large number of users.

Other objects and advantages of the invention will be apparent from the following description and the accompanying drawings, in which similar characters of reference indicate similar parts throughout the several views.

Referring to the two sheets of drawings,

Fig. 1 is a view in perspective of a sanding machine constructed according to the present invention and including the driving motor and flexible shaft;

Fig. 2 is a side elevational view taken from the rear side of Fig. 1;

Fig. 3 is a sectional view taken on the plane of the line 3—3 of Fig. 2, looking in the direction of the arrows;

Fig. 4 is a sectional view taken on the plane of the line 4—4 of Fig. 2, looking in the direction of the arrows;

Fig. 5 is a sectional view taken on the plane of the line 5—5 of Fig. 2, looking in the direction of the arrows;

Fig. 6 is a sectional view, taken on the plane of the line 6—6 of Fig. 2, looking in the direction of the arrows;

Fig. 7 is a top plan view of the abrasive backing member with the supporting shank in section, taken on the plane of the line 7—7 of Fig. 2; and

Fig. 8 is a fragmentary sectional view showing the mode of fastening the heat insulating pad and the anti-friction metal covering for the abrasive backing member, taken on the plane of the line 8—8 of Fig. 7, looking in the direction of the arrows.

Referring to Fig. 1, 10 indicates in its entirety an improved sanding machine constructed according to the present invention, which may be driven by means of one or more lengths of flexible shaft 11 and a stationary electric motor 12. Of course, any type of electric motor may be used, including even the portable type, provided the motor is suitably mounted or held for operation as shown, and any type of flexible shaft may also be employed, the flexible shaft including an exterior housing 13 and the flexible or hinged driving elements of wires or links 14.

The sanding machine 10 is preferably supported and partially housed by means of a housing 15, which may be provided with a substantially flat top 16, a substantially flat side 17, but open at the bottom and preferably open at one side, as shown in Fig. 2.

The width of the top 16 is preferably slightly less than that required to cover above the abrasive belt 18 so that the edge 19 of the belt preferably projects slightly beyond the edge 20 of the housing top 16. At its free end 21 the housing may also be open, but at its rear end 22 it is preferably provided with an enlarged housing portion of sufficient size to house both the belt pulley at that end and the adjusting means for tensioning the belt.

For example, the housing enlargement 22 may be provided with a substantially flat top 23, a flat side 24, a substantially flat end 25, and a concave portion 26.

All of the metal parts of the device with the exception of the stock bolts and screws, shafts and bearings are preferably constructed of an aluminum alloy and of cast metal so that the device may be constructed as cheaply as possible and so that the complete assembly will be as light as is consistent with the strength required for the various parts. The enlarged housing portion 55

22 is preferably provided with a handle 27 of the spade handle type, having an intermediate grip portion 28 and laterally extending supporting portions 29, 30. The attaching flanges 31 and 32 of the handle are provided with suitable apertures for receiving the securing screw bolts 33 which pass through these apertures and are threaded into threaded bores in the housing 15.

Another knob-like handle 34, which may be 10 constructed of wood or aluminum alloy, is preferably secured to the top 16 of the housing by means of a screw bolt 35 which is located in a bore 36 and counterbore 37 in the knob 34 and threaded home into a threaded bore 38 in the 15 top 16. Knob 34 is adapted to be received in the ball of the hand, the fingers passing under the knob for lifting and manipulating the sanding machine.

Referring to Fig. 2, the housing 15 is provided 20 at the juncture between the enlarged portion 22 and the top 16 with a relatively thick upwardly extending flange 39. Flange 39 is provided with a pair of spaced transverse cylindrical bores 40 and 41 for passing a pair of guide bolts 42, 43 25 which carry a bearing bracket 44. The guide bolts 42, 43 are provided with nuts 45 at their outer ends for drawing the bearing bracket toward the flange 39, and the flange 39 is provided with a threaded bore 46 for receiving the threaded 30 screw bolt 47, the end of which bears against the bearing bracket 44 and urges it in the opposite direction away from the flange 39.

Bearing bracket 44 preferably comprises a cast metal member which is provided with a transversely extending arm 49 and a bearing supporting sleeve 50. The transversely extending arm 48 has two enlarged cylindrical lug portions 51 and 52 which are provided with cylindrical bores 53 for receiving the ends of the guide bolts 42, 43. Transverse threaded bores 54 are provided 40 for receiving short set screws 55 which bear against the guide bolts 42, 43 and secure these guide bolts in the bearing bracket 44. The bearing bracket arm 48 is provided with an upwardly 45 extending flange 56 joining the lugs 51, 52, and providing a bearing surface for engagement with the end of the screw bolt 47.

The depending arm 49 is preferably formed of a pair of flanges 57, 58 at right angles to each 50 other, thereby making the depending arm 49 of substantially T shape. The bearing supporting sleeve 50 extends with its axis substantially parallel to the transverse arm 48 of the bearing bracket 44, and sleeve 50 has a cylindrical bore 59 within 55 which are secured at each end the bearings 60, 61 of any suitable bearing metal. These bearings may be pressed in and secured by a close frictional fit, according to the usual bearing practice.

At its opposite end the housing 15 supports by 60 means of the flat wall 17 an integral cast metal bearing sleeve 62 having a cylindrical bore 63 within which are secured bearings 64, 65 of any suitable bearing metal. The bearings 60, 61 are 65 adapted to rotatably receive a drive shaft 66 which is provided with a knurled and tapered end 67 which is fixedly secured in the hub 68 of the drive pulley 69.

Drive pulley 69 comprises a substantially cylindrical cast metal member which is preferably 70 provided with a slight crown at the middle 70 so as to cause the belt to run toward the middle of the pulleys. The cylindrical body of the pulley 69 is joined to the hub 68 by a web 71 and a 75 metal washer 72 is preferably placed upon the

shaft 66 and interposed between the end of the bearing 61 and the web 71. The shaft 66 is preferably provided with another steel washer 72 at the outer end of bearing 60, and a thrust bearing may be provided on the shaft 66 by means of a cylindrical collar 73 having a threaded bore 74 for a set screw 75 which secures the collar on the shaft 66.

The outer end of shaft 66 may be provided with a threaded bore 76 or with any suitable form of connection for securement to the end 77 of the flexible shaft 11. Of course, the thread in the bore 76 is such that the end 77 of the flexible shaft is driven home in the bore when the pulley 69 is driven.

The substantially cylindrical surface 70 of the pulley 69 is covered with a relatively thick resilient and flexible cylindrical rubber tube 78. The rubber tube 78 grips the metal cylindrical surface 70 of the pulley and provides an anti-slip covering for engagement with the metal of the pulley and the interior of the abrasive belt.

The other pulley 79 is substantially identical in construction and is fixedly secured to a shaft 80 located in the bearings 64, 65. Similar washers 81, 82 may be employed, and shaft 80 is provided with a similar thrust bearing 83.

The pulleys 69, 79 support an abrasive belt 84 which may consist of a strip of abrasive material such as emery cloth, sand paper or sand bearing fabric, or any flexible abrasive material. The ends of the strip of abrasive material are cemented together, preferably along a diagonal line, in such manner as to provide a continuous abrasive belt which will fit over the two pulleys 69, 79 and be adapted to be drawn tight in between the pulleys. The upper part of the belt 84 is located immediately below the top 16, but out of contact therewith, the top of the pulleys being substantially below the inside of the top 16 of the housing. The lower part of the belt 84 is located substantially below the lower edge of the housing side 17 so that the housing may not interfere with the action of the abrasive belt.

The housing 15 is preferably provided on the 45 inside of its wall 17 with a relatively thick lug 85 adapted to support a backing member for the abrasive. The lug 85 is provided with a vertically extending bore 86 for receiving the shank 87 of the backing member. The cylindrical shank 50 87 may be secured in the bore 86 by a set screw 88 which is threaded into the bore 89. Backing member 90 is shown in plan in Fig. 7, and preferably consists of a cast metal member having a substantially flat bottom 91 and an upwardly 55 extending border flange 92.

A number of transverse reinforcing flanges 93 may be provided on the top, and the top is formed with an upwardly extending lug 94 having a cylindrical bore 95 within which is secured the 60 knurled end 96 of the shank or stub shaft 87 by a drive fit. The backing member 90 is preferably rectangular in plan and of a width substantially equal to the width of the belt, but preferably not extending beyond the belt, particularly at the 65 open side of the casing. Its length is such that it substantially fills the space between the pulleys 69, 79 inside the belt 84, and it is adapted to engage the flat portion of the belt at the bottom of the sanding machine between the pulleys 70 to reinforce and back up the abrasive belt at the point at which the belt is applied to the work.

As considerable heat may be generated due to the friction caused by the working of the abrasive on the work and by the sliding of the back of 75

the belt over the backing member 90, the backing member 90 is preferably covered with a pad of heat insulating material such as one or more layers of cork 91, 98 cemented firmly together and to the metal backing member 90 and co-extensive in area with the bottom of the backing member.

The backing member 90 is also preferably provided with a friction reducing covering such as a sheet steel member 99 of similar shape to the backing member and provided, as shown in Fig. 8, with an upwardly extending attaching flange 100.

The anti-friction apron 99 is preferably provided with a resilient outwardly extending rib 101, joining attaching flange 100 to the body of the apron 99. The attaching flange 100 is located at the leading end of the apron, that is, the end toward which the abrasive belt moves.

Thus the resilient portion 101 is adapted to give slightly and permit the apron 99 to adjust itself to the surface of the pad 91, 98 when pressure is applied to the abrasive, and thence to the backing member 90. The backing member 90 is, of course, adjusted so that it will engage the back 25 of the belt 84, and it may be so adjusted that it will cause the belt 84 to project slightly over the area of the backing member 90. Thus the backing member 90 shapes the belt 84 into a flat work engaging surface and provides a firm surface 30 for backing up the flexible abrasive belt when it is applied to the work. The belt should be arranged so that it is drawn taut by adjusting the bearing bracket 44 by means of screw bolt 47 and guide bolts 42, 43.

The operation of the sanding machine will be evident from the preceding description. The sanding machine may be grasped with the right hand on the handle 27 and the left hand on the knob 34 and applied to the work somewhat like 40 a plane or other portable tool. Due to the fact that the working belt comes to the very edge of the tool as depicted in Fig. 3 and there are no other projecting parts to interfere with the operation of the edge of the abrasive belt at this 45 point, the sander may be placed flatly against the wall at the edge of a floor, and practically the whole surface of the floor may be treated by means of the machine. Only a very small portion in the corners of the room need be made 50 the subject of hand sanding. The present sanding device may be used to sand in the direction of the grain or in any other direction relative to the grain, and when used in the former method it is adapted to produce a more finished 55 smoothing job than any sanding devices employing a rotary disc.

So far as I am aware, this is the first portable sanding device driven by a motor and flexible shaft and having a sanding belt with a flat work 60 engaging surface, and the present tool is adapted to perform its work more evenly than any of the devices of the prior art.

While I have illustrated a preferred embodiment of my invention, many modifications may be 65 made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. In a sanding machine, the combination of a cast metal housing provided with a top wall and a side wall, the bottom and other side being open,

handle means carried by said housing, said housing having an enlargement at one end with an upwardly extending offset wall, said side wall carrying a transversely extending bearing lug provided with a bore, bearing means in said lug, 5 a movable bearing support comprising a metal member having a pair of bores extending longitudinally of said housing and carried by a lug extending up into said enlargement adjacent said offset wall, a pair of rods secured in said bores, 10 said rods extending through bores in said offset wall and being slidably supported in said latter bores, and threaded means located between said rods and threaded into said offset wall for engaging said upwardly extending lug for moving 15 said bearing means to tension an abrasive belt, pulleys rotatably mounted on shafts in each of said bearing means, and an abrasive belt carried by said pulleys.

2. In a sanding machine, the combination of a 20 cast metal housing provided with a top wall and a side wall, the bottom and other side being open, handle means carried by said housing, said housing having an enlargement at one end with an upwardly extending offset wall, said side wall carrying a transversely extending bearing lug provided with a bore, bearing means in said lug, a movable bearing support comprising a metal member having a pair of bores extending longitudinally of 25 said housing and carried by a lug extending up into said enlargement adjacent said offset wall, a pair of rods secured in said bores, said rods extending through bores in said offset wall and being slidably supported in said latter bores, and threaded means located between said rods and 30 threaded into said offset wall for engaging said upwardly extending lug for moving said bearing means to tension an abrasive belt, pulleys rotatably mounted on shafts in each of said bearing means, and an abrasive belt carried by said pulleys, the top wall of said housing terminating 35 short of the free side of said pulleys and abrasive belt, whereby the abrasive belt is adapted to project beyond the walls of the housing to be brought into engagement with the work when located in a 40 corner.

3. In a sanding machine, the combination of a housing having a top wall and a side wall, said housing supporting bearings parallel to each other 50 at each end of the housing, a shaft in each of said bearings, a pulley carried by each of said shafts, said pulleys each comprising a cast metal member secured to said shaft by means of anchoring formations, and said pulleys projecting 55 beyond the walls of said housing at the open side of said housing, an abrasive belt mounted on said pulleys and likewise extending beyond the walls of said housing, whereby the housing does not interfere with the use of the abrasive belt 60 on work when located adjacent a wall or the like, said housing having a vertical wall supporting one of said bearings, an inwardly extending lug on said vertical wall located inside of said belt, said lug having a vertically extending bore, and a set screw in a transverse bore for projection into 65 said vertically extending bore, a cast metal backing member having an upwardly extending rod secured therein, said rod extending into said bore for securing in any predetermined adjusted 70 position by said set screw, said backing member being provided with a resilient covering on its lower side and an apron secured to said backing member at its leading end and comprising a polished metal member for slidably engaging the in- 75

ner side of the abrasive belt, said backing member being adapted to force the belt into engagement with a work piece.

4. In a sanding machine, the combination of
5 a housing comprising a top wall and a vertical side
wall, a pair of bearings supported by and at the
ends of the housing, said bearings having parallel
horizontal axes, shafts mounted in said bearings,
10 pulleys carried by said shafts, means for
driving one of said pulleys, an abrasive belt
mounted on said pulleys, a lug on the vertical
wall of the housing projecting into the space be-
tween the upper and lower runs of the belt, a ver-
15 tical bore in said lug, a metal backing member hor-
izontally disposed in the space between the upper
and lower runs of the belt, a vertical rod carried
by said backing member extending upwardly into
the vertical bore of the aforesaid lug, a set screw
20 whereby said rod may be secured at various posi-
tions in the lug bore, a resilient covering on the
lower surface of the backing member, and an
apron secured to the said backing member at its
leading end, said apron lying beneath the afore-
25 said resilient covering, presenting a smooth lower
surface to the upper surface of the lower run of
the belt, and serving yieldingly to urge the said

lower run of the belt into engagement with a
work piece.

5. In a sanding machine, the combination of
a housing comprising a top wall and a vertical side
wall, a pair of bearings supported by and at the 5
ends of the housing, said bearings having parallel
horizontal axes, shafts mounted in said bearings,
pulleys carried by said shafts, means for
driving one of said pulleys, an abrasive belt
mounted on said pulleys, a lug on the vertical 10
wall of the housing projecting into the space be-
tween the upper and lower runs of the belt, a ver-
tical bore in said lug, a metal backing member
horizontally disposed in the space between the
upper and lower runs of the belt, a vertical rod 15
carried by said backing member extending up-
wardly into the vertical bore of the aforesaid
lug, a set screw whereby said rod may be secured
at various positions in the lug bore, and an apron
secured to said backing member at its leading 20
end, said apron underlying the backing member,
presenting a smooth lower surface to the upper
surface of the lower run of the belt, and serving
yieldingly to urge the said lower run of the belt
into engagement with a work piece. 25

THERON L. HEDGPETH.
